DRUM DRIER

Charles O. Lavett, Buffalo, N. Y., assignor to
 Buffalo Foundry & Machine Co., Buffalo, N. Y.,
 a corporation of New York

Application October 15, 1935, Serial No. 45,092

4 Claims. (Cl. 159—11)

The invention relates to an atmospheric drum drier and more particularly to a drum drier for handling liquid materials which tend to become viscous and pasty and difficult to handle and remove when handled on drum driers of conventional types. More particularly the drier forming the subject of this invention is designed to handle such materials as whey, following the process shown and described in my copending application for patent, Ser. No. 152,616, filed July 8, 1937.

It is the object of the invention to provide a drum drier which operates, in two stages, to eliminate moisture from a liquid solution and convert it into a solid state in a short space of time and which is of high capacity and continuous operation thereby to permit of low cost operation and as a continuous process.

In the accompanying drawing:

Fig. 1 is a side elevation of a drum drier embodying my invention and showing the same discharging into a grinder and bagger.

Fig. 2 is a vertical transverse section, taken on line 2—2, Fig. 1.

In the atmospheric drum drier shown the solution is partially dried between an upper pair of drums 5 and 6 and then further dried between a lower set of drums 7 and 8. All of the drums are journaled in the usual end heads 9 and 10 of the supporting frame and the drums of each set are driven in opposite directions by means of gears 11 and 12, the speed of each set depending on conditions. Steam is admitted to each of the drums and the condensate removed therefrom by means of steam and condensate connections 13 and 14 extending through the spindles of the drums. The drums of the upper set are set close together and are provided at opposite ends with end boards 15 which are held against the ends of the drums in any suitable manner and form a reservoir 16 between the drums. Similarly, the lower pair of drums are provided at opposite ends with end boards 17 arranged against the ends of the lower pair of drums and forming a receiving space 18 between the lower pair of drums, the spacing between them being adjustable, by means of any well-known adjustment such as by the usual movable bearings and screw adjustments indicated at 29.

The upper pair of drums is driven by a pinion 19 in the opposite direction from the drums of a conventional double drum drier, i. e. the drums 5 and 6 travel upwardly at their point of closest approach. The lower drums 7 and 8 are driven by a pinion 20 in the opposite direction from the

upper set of drums, i. e. they travel downwardly at their point of closest approach.

The vapors generated during drying are carried away by means of a hood 21 and the solution is discharged from a pipe 22 into the reservoir 16 between the upper set of drums 5 and 6 and the end boards 15 at the ends of these drums.

An essential feature of the present invention resides in the rotation of the upper drums 5 and 6 upwards at their point of closest approach and 10 in the rotation of the lower set of drums 7 and 8 downward at their point of closest approach. By this means the solution is held in the reservoir 16, and is maintained in a liquid condition 15 and at its boiling point. The quantity of liquid in reservoir 16 is held for a time, which is sufficient to raise this liquid to the boiling point but not long enough to concentrate the liquid to such an extent that it becomes viscous or pasty. As the drums 5 and 6 rotate they pick up a heavy, thick 20 layer of the boiling liquid solution. All the material so adhering to the drum surfaces as they pass through the boiling liquid solution in reservoir 16 is retained undisturbed on the drum surfaces and is not partly removed and accumulated 25 before leaving this reservoir as is the case when the drums revolve in the opposite direction. The material adhering to the drum surfaces is quickly reduced to any desired moisture content which is governed by the density of the solution fed, 30 the steam pressure and the speed of the drums. This layer can be readily stripped from the upper drums by doctor blades 23 and dropped directly onto the lower pair of rolls 7 and 8 in a highly 35 viscous or pasty form. Since the lower rolls 7 and 8 rotate toward each other at their point of closest approach they are able to handle this viscous liquid by forcing said viscous liquid between the drums and against the drum surfaces so that said viscous liquid is pressed into a thick 40 film adhering to the under surfaces of the drums which emerge from their point of closest approach and can be quickly dried to any desired degree before being removed by doctor blades 45 24. A surplus of material may be allowed to accumulate in the receiving space 18 if desirable. The doctor blades 24 scrape the dry material into longitudinal screw conveyors 25 which in turn deliver the dry material to a cross conveyor 26. This cross conveyor 26 delivers the dry material 50 to an elevator 27 which discharges at 28 into a grinder 30 from which the material is deposited into suitable containers.

In using the double drum drier forming the subject of this invention the solution, if necessary, 55

is first concentrated preferably in a multiple effect vacuum evaporator to a concentration which can be effected with a continuous flow of material and without danger of discoloration. While a higher concentration frequently could be effected in an evaporator it is not desirable because often the liquid would not flow smoothly through the pipe 22 and upon being deposited in the reservoir 16 would quickly become viscous or pasty, 10 would thereupon not boil freely, would then often have a tendency to discolor and would not be deposited on the drum surfaces in a uniform and suitable coating.

This concentrated solution is deposited preferably without cooling to any great extent in the reservoir 16 and is held in this reservoir for a short time. The steam pressure in the upper drums 5 and 6 is preferably maintained at a suitable pressure, so that the solution so held in the 20 reservoir 16 boils freely and a considerable amount of water is evaporated. As the drums rotate upwardly at their point of closest approach each picks up a heavy layer of the boiling solution and quickly reduces it to any desired moisture content, which is controlled by the density of the liquor fed, by the level of said liquor in its reservoir 16, and by the steam pressure and speed of the drums. These layers are preferably reduced to a highly viscous condition, the drying period 25 of the layers on the drum surfaces being such that the quantity of viscous material produced is not in excess of the amount which is dried on the lower drums 7 and 8 in the same period of time. The heavy layers of viscous material are then scraped from the drums 5 and 6 by the doctor knives 23 and deposited directly on the lower pair of drums 7, 8. These drums immediately carry the partly dried material into the reservoir 18 between the lower pair of drums. As the 30 drums 7 and 8 rotate the material is gradually forced between these drums and against the drum surfaces so that a thick film of viscous material is deposited on the drum surfaces as they leave their point of closest approach and can be dried to any desired degree by regulating the clearance between the drums, the steam pressure and the drum speed.

It will be understood that the moisture content may be varied, if desired, by increasing or decreasing the clearance between the drums 7 and 8 by means of any usual and well known means, such as the movable bearings and screw adjustments indicated at 28, or by varying the steam pressure or drum speed. Actual steam pressure and time of contact allowed with both 55 sets of drums is regulated to correspond to the nature of the solution.

From the foregoing it is apparent that the drum drier forming the subject of this invention provides a low cost drier which will quickly reduce solutions to a dry stable form.

While the invention is particularly applicable to the drying of whey, it will be appreciated that the drier can also be used in drying other materials, particularly those having similar characteristics.

While I have shown specific apparatus and described a specific process capable of being performed therein, it will be understood that the invention is not to be limited to such specific apparatus or process but is to be accorded the full range of equivalents comprehended by the accompanying claims. In particular by the term "drier" as used herein is meant apparatus which eliminates moisture from a liquid being processed

and converts this liquid to a solid state regardless of the nature or condition of the media supplied to the several drums thereof.

I claim as my invention:

1. A two stage drier, comprising upper and 5 lower pairs of heated closely spaced drums each pair being arranged parallel with one another and having end boards forming a reservoir between the drums of each pair, means for depositing the material to be dried in liquid form in the upper reservoir, means for rotating the upper drums in the direction in which their surfaces travel upwardly at their point of closest approach whereby each upper drum picks up a heavy layer of liquid from the upper reservoir, 15 means for removing said layers from the lower parts of said upper drums and permitting them to fall by gravity onto the lower drums, means for rotating said lower drums in the direction in which their surfaces travel downwardly at their point of closest approach to thereby force the material falling from said upper pair of drums between said lower drums to be deposited and dried thereon in layers and means for removing the dried material from the upper parts of said 25 lower drums.

2. A two stage drier, comprising a pair of heated drums arranged parallel with one another and forming a valley therebetween, end boards at the ends of said drums and forming a reservoir in said valley, means for depositing the material to be dried in liquid form in said reservoir, means for rotating said drums in the direction in which their surfaces travel upwardly at their point of closest approach whereby each drum picks up a heavy layer of liquid from said reservoir, means for removing said layers from the lower parts of said drums, a second pair of drums arranged parallel to one another and directly under said first pair of drums and receiving the material falling by gravity from said removing means, means for rotating said second pair of drums in the direction in which their surfaces travel downwardly at their point of closest approach whereby the material dropping from said upper 40 pair of drums is forced between said second pair of drums and spread into layers thereon, means for maintaining said second pair of drums at such temperature as to convert said layers to a solid state and means for removing the solidified material from the upper parts of said second 45 pair of drums.

3. A two stage atmospheric drier, comprising upper and lower pairs of closely spaced drums each pair being arranged parallel with one another and having end boards forming a reservoir between the drums of each pair, means for depositing the material to be dried in liquid form in the upper reservoir, means for rotating the upper drums in the direction in which their surfaces travel upwardly at their point of closest approach whereby each upper drum picks up a heavy layer of liquid from the upper reservoir, means for heating said upper pair of drums, means for removing said layers from the lower 60 parts of said upper drums and permitting them to fall by gravity onto the lower drums, means for rotating said lower drums in the direction in which their surfaces travel downwardly at their point of closest approach to force the material falling from said removing means between said lower drums and spread the material into layers thereon, means for maintaining said lower pair of drums at such temperature as to convert said layers to a solid state and means for removing 65

solidified material from the upper parts of said lower pair of drums.

4. A two stage drier, comprising a pair of heated drums arranged parallel with one another and forming a valley therebetween, end boards at the ends of said drums and forming a reservoir in said valley, means for depositing the material to be dried in liquid form in said reservoir, means for rotating said drums in the direction 10 in which their surfaces travel upwardly at their

point of closest approach whereby each drum picks up a heavy layer of liquid from said reservoir, means for removing said layers from the lower parts of said drums, a heating surface arranged under said last means and onto which 5 said removed layers fall by gravity, means for heating said last heating surface and means for removing the dried material from said heating surface.

CHARLES O. LAVETT. 10
